[57] CLAIM

The ornamental design for a flotation device, as shown and described.

DESCRIPTION

FIG. 1 is a top, rear and right side perspective view of a flotation device showing my new design;

FIG. 2 is a top plan view thereof;

FIG. 3 is a rear elevational view thereof;

FIG. 4 is a front elevational view thereof;

FIG. 5 is a bottom plan view thereof; and,

FIG. 6 is a right side elevational view thereof, the left side being a mirror image, which illustrates one use of my new design. The broken lines showing of an occupant using the device is for illustrative purposes only and forms no part of the claimed design.
